BIB STRUCTURE

Adda M. Allen, Arlington, Va.

Application February 4, 1948, Serial No. 6,282

1 Claim. (Cl. 2—49)

1

The present invention is a bib of cheap and simple construction which is useful for protecting the clothing of the wearer. While not necessarily confined to any one use, the bib disclosed herein will be found to be particularly useful for wear by infants and children to protect their clothing when eating.

A principal object of the invention is to provide a bib for the above purposes which can be used on one occasion and then be disposed of, the cheapness of the materials and construction making such manner of use practical.

Another important object of the invention is to provide a bib of cheap and simple construction which can be adjusted when worn by a child, so as to entirely protect the front of the child's clothing. As described herein, the bib structure includes a novel arrangement of pleats and folds whereby it may be bowed outwardly along a substantially central lateral line to provide a protruding shelf or ledge generally located beneath the child's chin, to catch particles of food or liquid which might otherwise fall to the floor or on the lower part of the child's clothing.

As is stated above, the invention seeks simplicity and cheapness, whereby it is economical to use such a bib only once. In this connection, the bib includes a front face or ply of soft, thin, water-absorbent material, such as paper tissue, whereby after one use, the forward face may be employed to wipe the baby's mouth or face before the bib is thrown away.

In the drawings, which disclose several forms of the invention which I have found to be useful:

Figures 1 through 4 are perspective views of different bibs made in accordance with the invention, that of Figure 1 being the preferred form;

Figure 5 is a sectional view taken along the line 5—5 of Figure 1, illustrating the construction of the bib adjacent its neck band;

Figure 6 is a perspective view of a bib of the general design of Figure 1, showing the same folded along a lateral line, this being the condition of the bib as it would be sold;

Figure 7 is a view looking toward the inside of the bib, showing the manner in which it is stretched and bowed outwardly along a central, lateral line to entirely cover the front of the baby's clothing and to form the protecting ledge previously referred to, and

Figure 8 is a view illustrating the general appearance of the outside of the bib, when worn by a child, after it has been stretched and bowed in the manner illustrated in Figure 7.

2

Referring to Figure 1, the bib proper comprises a back sheet 10 and a generally co-extensive overlying front sheet 12. The back sheet may be made of any suitable waterproof material, 5 in order to provide protection for the clothing against liquids. Various synthetic materials now on the market would be useful for this purpose, and I have in mind such as cellophane, "Pliofilm," or "Polyethlyne." The last named material is described in some detail in my copending application, Serial No. 717,105, filed December 19, 1946, now Patent No. 2,550,034, dated April 24, 1951, page 11, and such description is made a part hereof by reference. It will be understood that any other suitable materials, such as rubberized materials, or materials impregnated with liquid-proof substances, would be suitable, although for purposes of appearance as well as general utility, I prefer the synthetic transparent 20 materials referred to.

The overlying front sheet 12 is preferably made of a soft, thin, water-absorbent material, such as commercial tissues now on the market for similar purposes, although a thin cloth material 25 would be adapted for the purposes of the invention.

In the manufacture of the bib, a flat front sheet 12 is placed over a flat back sheet 10, and, thereafter, suitable longitudinal folds are made 30 in the sheets throughout the length of the bib, to provide a pleated construction. It will be understood that the pleated construction is for a useful purpose, as hereinafter described, as well as enhancing the appearances of the bib. 35 For example, the two plies of material are creased along opposite symmetrically disposed lines 14 and 16 to provide outwardly presented folds, as indicated at 18, and the two plies of material are again creased in the opposite direction along symmetrically disposed longitudinal lines nearer to the center line of the bib to provide inwardly presented folds as indicated at 20. The resulting construction then includes a relatively broad central panel 22, and spaced 40 underlying outer panels 24, the construction 45 being such that the panels are related in bellows like manner.

After the two plies of material are assembled and folded in the pleated manner as described, 50 a short area at the upper end of the bib is creased or folded inwardly along the line 26, as more particularly shown in Figure 5, whereby there is a short band of the soft water-absorbent material positioned against the front of the child's neck 55 when the bib is being worn. A neck encircling

band 28 is provided to tie or otherwise secure the bib around the child's neck. As illustrated in Figures 1 and 5, this band is secured between the rear face of the waterproof back sheet 10 and that edge area 30 of said back sheet which is folded rearwardly along the line 26. It will be understood that when the edge area 30 is folded rearwardly around the band 28, it may be permanently secured by the application of heat and pressure to the rear side of the back sheet 10, the film material of which the back sheet is made, being such that layers thereof will bond together upon application of heat and pressure. If found more expedient, the folded area 30 may be adhesively secured to the rearward surface of the back sheet 10.

While I have shown the neck band 28 as being conveniently secured in one piece to the bib proper, in the manner just described, it will be understood that an acceptable variation in the structure would include a neck band comprising separate tapes otherwise attached to the bib proper, as by bonding or adhesively securing the tapes to the rearward surface of the back sheet 10. The neck band 28 may be made of cloth, or may be made of the same film-like material described as being useful in forming the back sheet 10.

Figures 2, 3, and 4 disclose modifications of the invention, differing only in the manner in which the pleats or folds are formed.

In the modification of Figure 2, there is a central panel 34 formed in the same manner as the central panel 22 of Figure 1, except that this central panel is narrower in its lateral dimension. In this embodiment, the underlying panels 38 are also narrower than the corresponding panels 24 of Figure 1, and additional rearwardly presented folds 38 and forwardly presented folds 40 are made in the material to provide additional front panels 42, the material being further provided with respective forwardly and rearwardly presented folds 44 and 46 whereby the bib includes additional outer spaced underlying panels 48.

In this modification, and in the modifications of Figures 3 and 4, there is a lateral crease 50 at the top edge of the bib to secure the neck band 28 and to provide an area of the soft water-absorbent material presented to the neck of the wearer.

Figure 3 discloses a further variation wherein successive outwardly presented longitudinal folds 52 are provided in the two plies of the material, and underlying each such fold are successive inwardly presented folds 54 whereby a pleated structure of step-like form, from one longitudinal edge of the bib to the other, is provided. In all other respects, the construction of this embodiment is similar to those previously described.

In Figure 4, a structure quite similar to Figure 1 is disclosed, including a relatively wide central panel 56 defined by outwardly presented folds 58 and overlying partially covered intermediate panels 60. However, in this design, unlike that of Figure 1, the panels 60 terminate in outwardly presented folds 62, and the material is further creased to provide additional inwardly presented folds 64 whereby additional border panels 66 are provided.

In all of the embodiments described above, it will be obvious that the bib may be expanded by pulling the opposite edges outwardly in order to

cover a greater area of the clothing of the wearer. In all of the embodiments shown, the pleats are formed by folds in both plies of the material, the two plies being assembled with the sheet 12 overlying the sheet 10, after which the folds are made in both sheets, as described.

I have found that bibs of the above description may be more conveniently packaged if they are also provided with a substantially central lateral or transverse fold along the line 68, as shown in Figure 6. This view discloses a bib of the type of Figure 1 folded along a central lateral line, but it will be understood that the bibs of the construction shown in the other figures may be similarly folded, as indicated. In addition to convenience in packaging, I have found that a lateral fold as at 68, either made by creasing when the bib is manufactured, or made in the material when the bib is to be used, permits the bib to be expanded in the manner shown in Figures 7 and 8, and to retain its shape when expanded as shown. When the bib is applied to the wearer, it is in the condition of Figure 1, and with a fold or crease 68 extending substantially centrally and laterally across the bib. Figure 7, a view looking toward the inside of the assembly, shows the manner in which the bib may be expanded by grasping opposite sides thereof at the ends of the lateral fold 68, and applying outward pulling forces as indicated by the arrows in Figure 7. When the edges of the bib are pulled outwardly in this manner, the back sheet is caused to bow outwardly along the line 68, provided a protruding ledge or shelf, as shown in Figure 8, generally beneath the chin of the wearer. Beneath the ledge thus formed, the material drapes downwardly in a generally vertical direction, as shown in Figure 8.

I have found that with a structure folded as just described, the ledge formed along the line 68 will be substantially self-sustaining, by reason of the fact that the elasticity of the material is destroyed along its lines 18, 20, and 68, whereby when it is pulled to its bowed-out condition, it will tend to remain in such condition. This is particularly true of the material at the opposite points 70, where the inwardly presented folds 28 cross the lateral fold 68, the material at these points being forced outwardly by the pulling action to a position beyond that where they are capable of returning to the undistorted position they occupied prior to the application of the pulling forces illustrated in Figure 7. In a similar manner, but to a lesser extent, the material at points 72 is forced outwardly beyond a point where it is capable of returning inwardly under its own elasticity.

While the outer ply 12 is shown pleated with the inner ply of material 10, it will be understood that it is the folds in the inner or back ply which provide the capability of expansion of the bib to the condition shown in Figures 7 and 8, and the retention of this condition, as previously described. That is, the sheet 10 is of such stiffness that when the continuity of its longitudinally folded lines is broken and when it is forced outwardly along a lateral line 68, it will sustain itself in this expanded condition, whereby the outer and softer ply of material 12 is likewise held in an expanded condition, although the outer ply is made of material which would be incapable of sustaining itself in such expanded condition.

It will be obvious from the above that I have provided a bib of simple and cheap construction,

which can be machine manufactured in such quantity as to be marketed at a price whereby a bib can be used once, and then be disposed of. In addition, the pleated construction provides fullness where needed. It may be left in the flat condition of Figure 1, or adjusted to the wider or expanded condition, as shown in Figure 8. It provides a full center area beneath the chin of the wearer.

It will be understood that the various folds described herein may be made permanent by the application of heat and pressure, or merely by the application of pressure. The lateral fold 68 may be made in the bib before it is packaged for sale, or a bib of the construction shown in Figures 1 through 4 might be laterally folded by the purchaser prior to use, in order to have the capabilities of assuming the expanded condition illustrated in Figure 8.

When the bib is used by a child, and is expanded to its unpleated condition as in Figure 8, it will be evident that the outer ply of soft material is substantially separated from the inner ply of water-proof material whereby the outer ply may be lifted by hand to wipe the baby's mouth, after which the entire bib may be removed and disposed of. In wiping the baby's mouth, it is not necessary to also use the back sheet 10, as the two sheets will readily separate at the lower end of the bib as described.

I claim:

A disposable bib having a body comprising a back sheet of thin pliable waterproof material and a front sheet of soft liquid absorbent material, said sheets being reversely folded along spaced longitudinal lines extending throughout the length of said body to provide interfitting pleats, said body being folded rearwardly along a lateral line adjacent the upper end thereof providing an end band comprising an outer ply

of said soft liquid absorbent material presented to the neck of the wearer and an inner ply of said waterproof material, and a neck encircling strap connected to extend from opposite sides of said body adjacent the upper end thereof, said back sheet having a lateral crease formed therein substantially centrally of the length of said body, whereby said body may be laterally stretched and outwardly bowed to open said pleats along said crease when the bib is being worn to provide a self-sustaining protruding ledge beneath the chin of the wearer, said inner ply of said band being bonded to the rearward face of said back sheet to maintain the interfitting pleated relationship of said sheets at the upper end of said body while said pleats are maintained in open condition along said crease.
